Inventor
George Kuhar,

By *Clarence A. O'Brien*

Attorney

UNITED STATES PATENT OFFICE.

GEORGE KUHAR, OF CHICAGO, ILLINOIS.

PLUMB TROWEL.

Application filed June 3, 1926. Serial No. 113,454.

The present invention relates to a plumb trowel such as is used by brick layers and the like, and has for its prime object to provide a combination with features of a trowel 5 which has a spirit level incorporated in the handle thereof so that the trowel blade may be placed against several bricks to ascertain whether or not said bricks and wall they form part of, are plumb.

Another very important object of the invention is to provide a tool of this nature which is exceedingly compact and convenient in its construction, simple, inexpensive to manufacture, handy, efficient and reliable, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:—

Figure 1 is a plan view of the trowel embodying the features of my invention,

Fig. 2 is an edge elevation,

Fig. 3 is an enlarged detail section through the end of the handle of the trowel, 30 and

Fig. 4 is a plan view of said end.

Referring to the drawing in detail, it will be seen that the numeral 5 designates the blade of the trowel which is formed on the shank 6 having the usual extension 7 disposed at an oblique angle to the plane of the blade 5. A handle 8 is mounted in any suitable manner on the extension 7 on the shank 6, and the extremity thereof is provided with a recess 9 having a slanting bottom 10 which is disposed at a right angle to the plane of the blade 5.

A spirit level 11 is mounted in the recess

9 to rest on the bottom 10 thereof. A transparency such as a glass panel 12 is disposed over the recess 9, being held in place by a flanged sleeve 14.

With this trowel, it is possible for the brick layer to use it in the usual manner that any ordinary trowel is used. The brick layer may, also, place the bottom face of the blade 5 against several bricks and by reading the spirit level 11 may ascertain whether or not said bricks are plumb. Obviously, a tool of this nature is much more handy than an ordinary plumb level, because the spirit level itself is disposed a spaced distance from the wall where it may be easily and conveniently read and furthermore the handle may be steadily grasped in the hand while the blade 5 is applied to the wall, and the spirit level may be conveniently and accurately read.

Having thus described my invention, what I claim as new is:—

1. A tool of the class described including a blade having a shank extending therefrom at an obtuse angle thereto, a handle on the shank and provided in its extremity with a recess, the bottom of which is disposed at a right angle to the plane of the blade, and a spirit level mounted in the recess on the bottom thereof.

2. A tool of the class described including a blade having a shank extending therefrom at an obtuse angle thereto, a handle on the shank and provided in its extremity with a recess, the bottom of which is disposed at a right angle to the plane of the blade, a spirit level mounted in the recess on the bottom thereof, a transparency over the recess and a flanged sleeve for holding said transparency on the handle.

In testimony whereof I affix my signature.

GEORGE KUHAR.
